BANK COMPRESSING APPARATUS

Eugene L. Malhiot, Maywood, Ill., assignor to
 Western Electric Company, Incorporated, New
 York, N. Y., a corporation of New York

Application April 15, 1947, Serial No. 741,502

7 Claims. (Cl. 29—238)

1

This invention relates to a compressing apparatus and more particularly to an apparatus for simultaneously compressing a pair of step by step banks to permit the clamping bolts thereof to be tightened.

It is an object of this invention to provide an improved apparatus for compressing articles.

In accordance with one embodiment of the invention, there is provided a base plate on which a compressing head is mounted for vertical reciprocatory movement with respect to a drawer, having a nest for supporting a pair of banks side by side and slideable on the plate from a loading position, where the banks may be placed in or removed from the drawer, to an operative position where the banks are located in a predetermined position under the compressing head and under a pair of pressure plates also mounted under the compressing head and connected together by a pair of equalizing links. A fluid actuator responsive to the movement of the drawer to its operative position operates to move the compressing head downwardly to carry aligning pins thereon to aligning position with respect to the parts of the bank and thrust members on the compressing head engage the equalizing links and through them transmit an equal pressure to the pressure plates for compressing the banks. The banks in their compressed condition may then have their clamping bolts tightened by tools applied through suitable apertures in the apparatus.

The invention may be more fully understood from the following description when considered in connection with the accompanying drawings illustrating the preferred embodiment of the invention wherein

Fig. 1 is a side elevational view of the apparatus with parts broken away and parts shown in section;

Fig. 2 is a diagrammatic view of the fluid actuator of the apparatus and the electrical control circuit for controlling the operation thereof;

Fig. 3 is a fragmentary plan view of the apparatus with a portion of the housing broken away and with the loading drawer thereof shown in its open position;

Fig. 4 is a plan sectional view of the apparatus taken on the line 4—4 of Fig. 5 showing the drawer moved to its closed position;

Fig. 5 is a transverse vertical sectional view taken on the line 5—5 of Fig. 4;

Fig. 6 is a fragmentary plan sectional view of a portion of the apparatus taken on the line 6—6 of Fig. 5;

Fig. 7 is a vertical longitudinal sectional view

of a portion of the apparatus taken on the line 1—1 of Fig. 4;

Fig. 8 is an enlarged side elevational view of a portion of the loading drawer of the apparatus with parts shown in section;

Figs. 9 and 10 are detailed sectional views taken on the line 9—9 and 10—10 of Fig. 8, respectively;

Fig. 11 is a plan view of the step by step bank of the type which may be compressed in the present apparatus; and

Fig. 12 is an enlarged fragmentary sectional view of the bank taken on the line 12—12 of Fig. 11.

The apparatus herein disclosed is designed to compress step by step banks 15 by simultaneously applying a predetermined equal pressure to a pair of banks which may vary slightly in height so that, while they are held in a compressed state, the clamping bolts passing therethrough may be tightened to retain the banks in their compressed condition. The banks 15 (Figs. 11 and 12), comprise a plurality of card units loosely clamped together in superposed relation between upper and lower clamping plates 18 and 19, respectively, and held in assembled relation by a plurality of clamping bolts 20. The hexagonal heads 21 of the bolts 20 engage the upper clamping plate 18, the shanks of the bolts 20 pass through aligned apertures in the clamping plates and the card units, and the threaded lower ends of the bolts threadedly engage the threaded apertures in the lower clamping plate 19. Apertures 25—25 are formed in the card units to facilitate the proper alignment thereof and apertures 27—27 are provided in the projecting ends of the clamping plates 18 and 19, whereby the bank may be mounted on framework (not shown).

The compressing apparatus generally comprises a base plate 31 (Fig. 1) mounted in a suitable table or bench (not shown) and a compressing head 32 reciprocably mounted on the base plate 31 and operatively connected to a fluid actuator 35 operable under control of an electrical control system. A drawer or tray 37, provided with a nest 38 to receive a pair of banks 15 side by side, is slidably mounted on the base plate 31 to position the banks underneath the compressing head 32, having a plurality of aligning pins 39 and 40 (Figs. 5 and 7) extending downwardly therefrom and under a pair of pressure plates 42 and 43 connected together by a pair of equalizing links 44—44, through which the pressure of the compressing head is transmitted equally to the pressure plates for compressing a pair of banks 15.

The compressing head 32 comprises an inverted channel member or cross head 46 secured to the upper ends of a pair of spaced, vertically reciprocable rods 48-48 mounted in guide members 50-50 on the base plate 31. The rods 48-48 pass through the guide members 50 and the plate 31 and are secured at their lower end to a channel-shaped cross head 52, from the lower central portion of which extends a lug 54. The cross head 52 has upwardly extending lug portions 53-53 engageable with the base plate 31 to limit the upward movement of the heads 32 and 52. The flattened sides of a pin 56 rotatably mounted in the lug 54 engage in the slotted end of a lever 58, fulcrumed at 59 to a bracket 60 mounted on the underneath side of the table 31. The other end of the lever 58 is pivotally connected to a piston rod 62 of the fluid actuator 35, which is supported from the under side of the table 31 by a bracket 64.

The sliding drawer 37 comprises a bottom wall 66 in the form of a flat plate having a central recess 67 and a pair of side portions 68 and 69. A block 70, on the upper surface of which is formed the seat or nest 38, is secured to the bottom wall 66. Positioned on the block 70, in a predetermined location, are the apertured, tapered aligning pins 72-72 adapted to fit into the apertures 27-27 of the lower clamping plate 19 to accurately position the banks 15 on the nest 38. The block 70 is provided with an irregular groove 72 (Fig. 3) and recesses 74 to accommodate the embossments on the clamping plate 19 and the ends of the clamping bolts 20, respectively, of the banks 15. A front wall 75 extends upwardly from the bottom wall 66 and has a handle 76 secured thereto, by means of which the drawer may be moved from one position to another.

Rollers 73 and 79 (Figs. 3, 4, 8 and 9) rotatably carried by brackets 80 and 81, which are yieldingly mounted on the side portions of the bottom wall 66, support the drawer 37 for free rolling movement on the base plate 31. The brackets 80 and 81 are mounted for vertical movement on shouldered studs 83 secured to the bottom wall 66, and are urged into engagement with the wall 66 by coil springs 85 mounted on the studs 83. The rollers 73 and 79 are rotatably mounted on pins 86 secured to depending lugs 87 extending downwardly from brackets 80 and 81. The parts are so arranged that the rollers normally support the drawer 37, with its bottom wall 66 spaced from the base plate 31 to provide free and easy rolling movement of the drawer and to permit vertical movement of the drawer relative to the rollers into engagement with the base plate 31 during the compressing of the banks 15. The drawer 37 is positioned between the rods 48-48 and underneath the compressing head 32 and is guided for reciprocatory movement on the base plate 31 by a plurality of rollers 90-90 engaging upwardly extending guide rails 92-92 on the base plate 31. The guide rails 92 are relieved at 93 to provide clearance for the rollers 90 when the drawer 37 is in its closed position (Fig. 4) so that the drawer, in this position, is free to move laterally, slightly, if necessary, when the aligning pins 39 and 40 on the compressing head 32 engage the apertured pins 72 on the drawer. A stop member 94, engageable with the front wall 75 of the drawer, limits its movement in the forward direction and a stop 96 on the base plate 31 is adapted to be engaged by a member 98 adjustably mounted in the block 70 to limit the

movement of the drawer in the rearward direction.

A pair of banks 15 may be placed on the nest 38 when the drawer 37 is in its open position, as indicated in Fig. 3, after which the drawer may be moved to the closed position, as indicated in Fig. 4, to locate the banks in a predetermined position underneath the pressure plates and in substantial alignment with the aligning pins 39 and 40. The aligning pins 39 and 40 are secured to the underneath side of the cross head 46 by a retaining plate 96 and a backing plate 97. The aligning pins 40, with their tapered ends, are arranged to enter the apertures 25 in the relatively loosely assembled card units 17 of the banks 15 to properly align the card units. The lower ends of the aligning pins 39 are formed with cylindrical and tapered surfaces 99 and 100, respectively, adapted to engage in the aperture of the aligning pins 72 of the drawer 37 to coaxially align the aligning pins 39 and 72. The upper portions of the aligning pins 39 are formed with tapering portions 101 and a cylindrical portion 102, which latter portions are adapted to fit into the apertures 27 in the upper clamping plates 18 of the banks 15 to aid in the proper alignment of the clamping plates 18.

The pressure plates 42 and 43 are suitably apertured at 104 and 105, respectively (Figs. 5, 6 and 7), to provide clearance for the aligning pins 39 and 40, and are also provided with a series of apertures 106 to provide clearance for the heads 21 of the clamping bolts 20 in the banks 15. Each of the pressure plates is mounted for vertical movement on three guide rods 109 and is moved upwardly against its respective head 110 on the rods by coiled springs 111. Extending upwardly on the pressure plates and intermediate their ends are lugs 114, in which pivot pins 115 are secured. The pivot pins 115 engage in apertures in the ends of the pressure equalizing links 44 and serve to pivotally connect the links to the pressure plates. Intermediate their ends, the links 44 are recessed, as at 117, to receive cylindrical pressure transmitting members 118 mounted on the compressing head 32.

The parts are so arranged that, with a pair of banks properly positioned underneath the compressing head, the aligning pins, as the compressing head 32 moves downwardly, will properly align the individual card units and the clamping plates of the banks, after which the thrust members 118 will engage the equalizing links 44 and move the pressure plates 42 and 43 downwardly to apply an equal predetermined pressure simultaneously to each of the pair of banks thereunder. With the banks in this compressed condition, a tool passed through aligned apertures 120 in the cross head 44, the retaining and backing plates 96 and 97, respectively, and the apertures 106 in the pressure plates may be applied to the heads 21 of the clamping bolts 20 to tighten them to a predetermined degree of tightness.

In order to prevent the fluid actuator from lowering the compressor head 32 except when the drawer 37 is in its closed position so that the banks are properly located under the compressing head, a safety device is provided comprising a movable segmental plate 125 (Figs. 1, 3 and 4) positioned on the underneath side of the base plate 31 and mounted on a pin 126 for rocking movement about a vertical axis. The plate 125 is interposed between a rod 128 forming an extension of the piston 62 and an aperture 129 formed in the base plate 31, through which aperture the rod

128 is adapted to move during the operation of the actuator 35. The pin 126, on which the segmental plate 125 is secured, is rotatably mounted in and extends through the base plate 31 and has secured to it, at its upper end, one end of a lever 132. The other end of the lever 132 is slotted to receive a roller 134 mounted on the portion 69 of the bottom wall 66 of the drawer 37. When the drawer 37 is moved from an open to a closed position, the lever 132 is rotated through a predetermined arc and, in turn, rotates the segmental plate 125 from a position (Fig. 3) blocking the movement of the rod 128 to a position (Fig. 4) not blocking the rod 128. Thus it will be seen that the segmental plate 125 acts to prevent the movement of the actuator 35 when the drawer 37 is in the open position and permits the operation of the actuator and the compressor head 32 only when the drawer has been moved to its inner or closed position, at which time the banks are properly placed to be acted on by the compressing head 32.

The fluid actuator 35 comprises a piston 135 (Fig. 2) positively actuated in opposite directions within a cylinder 136 by a fluid admitted alternately to opposite ends thereof through a valve 137, which is moved from one operating position to another under control of a pair of solenoids 138 and 139 in an electrical control circuit. The solenoid 138 is connected to a line 141 of a pair of power supply lines 141 and 142 and is connected to the line 142 through the normally closed switch contacts 144 of a relay 146. The solenoid 139 is connected to the line 142 and, through normally open switch contacts 148 of the relay, is connectible to the line 141. The relay 146 is spring-returned to its normal operating position, indicated in Fig. 2, and may be actuated to its other operating position upon energization of the relay coil 150, which is connected to the line 142, and is connectible, through a normally open microswitch 152 and a microswitch 154, to the line 141. When the apparatus is in its normal non-compressing condition, with the head 32 up and with the drawer 37 open, a circuit is completed through the solenoid 138 and the closed contacts 144 to actuate the solenoid valve 137 and hold it in a position where it causes the actuator 35 to move and maintain the head 32 in its raised position.

The microswitch 152 (Figs. 1, 3 and 4) is mounted on the upper side of the base plate 31 in the path of movement of the end of the drawer 37 and is adapted to be engaged and closed by a member 156 adjustably mounted on the end portion of the bottom wall 66 thereof when the drawer is moved to its rearmost or fully closed position, as indicated in Fig. 4. When the microswitch 152 is closed, the circuit to the relay coil 150 is completed, causing the energization thereof and the actuation of the relay 146 to its operated position. This causes the deenergization of solenoid 138 and the energization of the solenoid 139 to effect the movement of the control valve 137 to its other position, resulting in the upward movement of the piston 135. The rod 128, moving upwardly with the piston 135, actuates the microswitch 154 in its path to cause the switch lever 158 to disengage the contact 159 and engage the contact 160. The contact 160 is connected in series with switch contacts 162 of the relay 146 and serves to complete a holding circuit through switch contacts 162 for locking the relay 146 in operated position.

When the compressor head 32 is moved down-

wardly by the upward movement of the piston 135, the tapered ends of the aligning pins 39 and 40 carried thereby enter the apertures 25 in the card units 17 on the banks 15 and cause a slight forward movement of the drawer 37 as the banks 15 are properly aligned by the aligning pins. This slight forward movement of the drawer 37 opens the microswitch 152. The actuator 35 causes the compressor head 32 to apply a predetermined pressure to the banks, which continues until the tightening operation is completed, after which the movement of the actuator 35 and the compressor head 32 may be reversed by the opening of a switch 166 connected in the line 142. The opening of the switch 166 breaks the circuit to the coil 150 and causes the return to normal of the relay 146 which, in turn, causes the reversal of the valve 137 and the consequent movement of the piston 135 to the position shown in Fig. 2.

A plunger 168 (Fig. 4), mounted on base 31 for reciprocable movement in a housing 169 and urged forwardly by a spring 170, is provided to engage the end of the bottom wall 66 of the drawer 37 when the drawer is in its closed position and apply pressure to the drawer, tending to move it to open position so that, on completion of the return stroke of the compressor head 32, and as soon as the aligning pins are withdrawn from the banks 15, the drawer 37 is moved forwardly a short distance. This short forward movement of the drawer further separates the microswitch operating member 156 from the microswitch 152 and thereby eliminates the possibility of accidental reactivation of the switch 152.

A protective housing is provided to substantially enclose the entire apparatus above the plate 31 and comprises a stationary housing 175 (Figs. 1, 3, 4, 5, 6 and 7) having side walls 176-176, a top wall 177, transverse wall portions 178 and 179, and front wall portions 180 and 181, which latter are spaced apart to provide an opening sufficient to receive the front wall 75 of the drawer 37. The movable portion 182 is rectangular in shape and comprises vertical end walls 183-183 and front and rear walls 184 and 185, respectively, joined to a top wall 186 and arranged in telescoping relation with portions of the stationary housing 175, as illustrated in the drawings, particularly Figs. 1 and 5. The movable housing 182 is mounted on the cross head 46 for reciprocation therewith and is secured thereto by means of screws 187. The top wall 186 is provided with a central opening 188 positioned in alignment with the channel of the cross head 46 to permit access to the apertures in the various members through which the tightening tools may be inserted during the operation of tightening the clamping bolts 20 in the banks 15. It will thus be seen that when the drawer is closed, the upper portion of the apparatus above the base plate 31 is entirely enclosed by the housing 175 and the wall 75 of the drawer 37, except for the opening 188, through which the bolt tightening tools 65 may be applied to the bolts 20 of the banks being compressed.

In the operation of the compressing apparatus, with the drawer 37 in its open position, a pair of banks are placed on the nest 38 thereof with the aligning pins 72-72 fitting into the apertures 27 of the lower clamping plate 19 of the banks 15. The operator then pushes the drawer rearwardly to a closed position until the member 98 engages the stop 96 to stop the drawer in its operative position, in which position the banks

are located under the pressure plates 42 and 43, compressing head 32 and with the apertures 25 thereof in substantial alignment with the aligning pins 39 and 40. During the rearward movement of the drawer, the safety plate 125 is rotated in a counter-clockwise direction from a position in the path of movement of the rod 128 of the actuator 35 to the position shown in Fig. 4, where the rod 128 is free to move upwardly. When the drawer 37 is moved to its closed position, the member 156 on the rear portion thereof engages and closes the microswitch 152 and completes the circuit to energize the relay 146 and cause the energization of the solenoid 139 to shift the valve 137 and effect the actuation of the actuator 35 and the downward movement of the compressor head 32. As the piston 135 of the actuator 35 moves upwardly, the rod 128 thereon engages the microswitch 154 and moves the switch lever 158 from engagement with the contact 159 into engagement with the contact 160, which completes a holding circuit for the coil 150 through the holding contacts 162. As the compressing head 32 moves downwardly, the aligning pins 39 and 40 carried thereby enter, respectively, the apertures 27 and 25 in the upper clamping plate and the card units of the banks 15 and serve to align the parts of the bank relative to each other. This aligning of the parts of the banks causes the drawer 37 to be moved forwardly a slight distance on the order of $\frac{1}{2}$ ", which allows the microswitch 152 to be moved from its closed to its normally open position. As the compressing head 32 continues its downward movement, the thrust members 118 carried thereby engage in the notches 117 of the equalizing links 44 and transmit the downward pressure of the head 32 through the links 44 to the pressure plates 42 and 43. The pressure plates 42 and 43 are thus moved downwardly into engagement with the pair of banks and apply a predetermined equal pressure there-to.

The bottom wall 66 of the drawer 37, which is normally supported for sliding movement on the plate 31 in spaced relation thereto, is moved into contact with the base plate 31, which serves as a backing member to receive the thrust of the pressure plates 42 and 44 and the head 32 during the compression of the banks. While the banks are thus under compression, and with the predetermined pressure being steadily applied thereto by the actuator 35, the operator may insert a tool through the aligned apertures in the compressing head and pressure plates to engage the heads 21 of the clamping bolts 20 and tighten them with a predetermined torque. After the clamping bolts 20 in each of the banks 15 have been tightened, the operator may press the button 168 to open the switch 166 in the line 142, deenergizing the coil 150 and allowing the relay 146 to be returned to its normal position. This will effect the reversal of the valve 137 and the actuator 35, causing the piston 135 and the compressing head 32 to return to their normal positions. On the upward movement of the head 32, the pressure plates 42 and 43 function as stripper members to strip the banks from the aligning pins 39 and 40. As the aligning pins 39 and 40 are withdrawn from the banks 15, the plunger 168, under the force of the spring 170, acts to move the drawer 37 forward a short distance so as to increase the distance between the member 156 and the microswitch 152 and thus avoid the possibility of an accidental or unintentional reclosing of the microswitch 152 and the initiation of another com-

pressing cycle of operation. The drawer 37 may then be moved forwardly to its open position and the tightened banks removed therefrom.

What is claimed is:

- 5 1. An apparatus for compressing a composite article comprising a supporting base member, an apertured movable head for compressing said article against said base plate, a pair of rods secured to said head and extending downwardly therefrom, apertured guide members on said base plate through which said rods extend and are guided for vertical reciprocation, a cross head secured to the lower end of said rods underneath said base plate, means operatively connected to 10 said cross head for actuating said compressing head, a drawer slidable on said base plate and having a bottom wall engageable therewith, a seat on said bottom wall for receiving an article thereon in predetermined position, means on said base plate for guiding said drawer for movement between an open position where an article may be applied to or removed from the drawer and a closed position where the article in the drawer is located in alignment with said head, an apertured housing secured to and movable with said head and having vertical wall portions surrounding said head, a stationary housing on said base plate enclosing portions of said apparatus and having vertical wall portions telescopingly en- 15 gaging said movable housing and provided with an opening in one vertical wall to accommodate the drawer, a vertical wall portion on said drawer adapted to close said opening in said vertical wall of the stationary housing when said drawer is closed whereby said apparatus above the base plate is entirely enclosed during the compressing operation except for the aperture in said movable housing through which aperture and the aperture in said compressing head a portion of 20 said article is accessible for further processing while under compression.
- 25 2. An apparatus for compressing a composite article comprising a supporting base plate, an apertured compressing head for compressing said article against said base plate, a pair of rods secured to said head and extending downwardly therefrom, guideways in said base plate through which said rods extend and are guided for vertical reciprocation, means including a fluid actuator operatively connected to the lower ends of 30 said rods for actuating said compressing head, a drawer slidable on said base plate and having a bottom wall engageable therewith, a seat on said bottom wall for supporting an article in predetermined position thereon, means on said base plate for guiding said drawer for movement between an open position where an article may be applied to or removed from the drawer and a closed position where the article in the drawer 35 is located in alignment with said head, a stationary housing on said base plate enclosing portions of said apparatus and having vertical wall portions disposed to partially encircle the compressing head and provided with an opening in one wall thereof to accommodate the drawer, a member extending from said head and having portions telescopingly engaging the vertical walls of the stationary housing, a vertical wall portion on said drawer adapted to close said opening in 40 the vertical wall of the stationary housing when the drawer is closed whereby said apparatus above the base plate is entirely enclosed during the compressing operation except for a portion of said compressing head through the aperture 45 in which a portion of the article is accessible for

further processing while under compression, and control means operable in response to the moving of the drawer to its closed position to cause the actuation of said actuator to effect the compressing movement of said compressing head.

3. An apparatus for compressing a pair of composite laminated articles comprising a base member, a head for compressing said articles against said base member, power means for actuating said head, means for supporting a pair of articles side by side on said base member in a predetermined position underneath said compressing head, a pair of pressure plates engageable with said articles, means on said base member for mounting said pressure plates independently of each other between said head and said base and for guiding said pressure plates for movement independently of each other toward and away from said base member, spring means yieldably supporting said pressure plates and for moving said pressure plates individually away from said base member, and a pair of pressure equalizing members pivotally attached at their ends to said pressure plates intermediate the ends of said plates and adapted to be pivotally engaged by said compressing head midway between the ends thereof whereby force transmitted by said head to said equalizing members will be distributed to the pressure plates for compressing each of said articles with equal pressure.

4. An apparatus for compressing a pair of composite laminated articles comprising a base member, a movable head for compressing said articles against the base member, means for reciprocating said head, a tray engageable with the base member and having a nest thereon for supporting a pair of said articles side by side in a predetermined position thereon, means on said base for guiding said tray for movement thereon between a loading position where the articles may be applied to or removed from the tray and an operative position where the articles are in alignment with said head, a pair of pressure plates individually engageable with said articles and actuatable by said head to transmit a predetermined pressure to said articles, and members pivotally connected at their ends to each of said pressure plates and intermediate their ends pivotally engageable with said head during the compression of said articles whereby said pressure plates are movable relative to each other to accommodate a pair of articles of different heights and are arranged to apply simultaneously equal pressures thereto.

5. An apparatus for compressing a pair of composite laminated articles having apertures therein comprising a supporting member to support said articles for compression, a movable head for compressing said articles against said supporting member, means for reciprocating said head relative to said supporting member, means for locating said articles side by side in a predetermined position on said supporting member in alignment with said supporting head, aligning members on said head and movable therewith into the aperture of said articles to align the component parts thereof, a pair of pressure plates underneath and in spaced relation to said head and said supporting member and engageable with said articles positioned on said supporting member, means guiding said pressure plates for movement individually toward and away from said supporting member, spring means for moving said pressure plates individually away from said supporting member, means for limiting

the extent of movement of said pressure plates away from said supporting member, a plurality of pressure equalizing members pivotally attached at their ends to said pressure plates, and thrust members mounted on said head and engageable with said equalizing members intermediate their ends, said pressure plates being arranged relative to said head so that on the down stroke of said head the aligning members engage the article and align the parts thereof before the head transmits its pressure through said equalizing members and pressure plates to said articles and on the up-stroke of said head the pressure plates act as stripper members to strip the articles from said aligning members.

6. An apparatus for compressing a pair of composite laminated articles each having aligning apertures in the component parts thereof comprising a base member, a movable head for compressing said articles against the base member, means for reciprocating said head relative to the base member, a tray engageable with the base member, means on said tray for supporting said articles side by side in a predetermined position thereon, means on said base member for guiding said tray for sliding movement thereon between a loading position where the articles may be applied to the tray and an operative position where the articles are in substantial alignment with said head, aligning members on said head and movable therewith into engagement with the aligning apertures in said articles to align the component parts of said articles, a pair of pressure plates engageable individually with said articles, means on said base member for individually mounting said pressure plates between said head and said base member and for guiding said pressure plates for movement toward and away from said base member, spring means for yieldably supporting said pressure plates and for moving said pressure plates away from said base member, means for limiting the movement of said pressure plates away from said base member, a plurality of pressure equalizing members pivotally connected at their ends to said pressure plates and pivotally engageable intermediate their ends with said head during the compressing of the articles whereby said pressure plates may move vertically relative to each other to accommodate articles of different heights and whereby the pressure equalizing members serve to transmit the pressure from the head simultaneously and equally to each of said pressure plates.

7. An apparatus for compressing a pair of composite laminated articles having aligning apertures therein comprising a base member, a pair of apertured pressure plates, members on said base for guiding said pressure plates for movement toward and away from said base, spring means yieldably supporting said pressure plates and for moving said plates away from said base, means for limiting the movement of said plates away from said base, pressure equalizing means comprising a member pivotally connected at its ends to the pressure plates intermediate the ends of said pressure plates, a tray having seats for supporting a pair of said articles side by side, means guiding said tray for movement on said base from a loading position where said articles may be loaded onto and unloaded from said tray to an operative position under said pressure plates, a cross head mounted for movement toward and away from said base, actuating means for reciprocating said cross head, means

on said cross head engageable with said pressure equalizing member intermediate its ends for applying predetermined pressure to said pressure equalizing member and said pressure plates, and aligning pins on said cross head movable into engagement with the aligning apertures in said articles to align the component parts thereof during the movement of said cross head toward said base, said pressure plates serving as stripping members to strip the articles from said aligning member during the movement of said cross head from said base.

EUGENE L. MALHIOT.
